UNITED STATES PATENT OFFICE.

JOHN EVANS, OF ELTHAM, ENGLAND.

APPARATUS FOR THE EXHIBITION OF PICTURES, ANNOUNCEMENTS, AND THE LIKE.

Application filed April 18, 1922. Serial No. 555,283.

To all whom it may concern:

Be it known that I, JOHN EVANS, a subject of His Majesty the King of England, and resident of Eltham, in the county of Kent, Kingdom of England, have invented certain new and useful Improvements in and Relating to Apparatus for the Exhibition of Pictures, Announcements, and the like, of which the following is a specification.

This invention refers to improvements in and relating to apparatus for the exhibition of pictures, announcements, advertisements and the like, and it has more particular reference to apparatus of the kind comprising a rotatable picture-carrying disc arranged in connection with a kinematograph projector or lantern, the device being driven from an electric motor by means of suitable gearing and an intermittent movement device.

The object of the present invention is to provide certain improvements in the operating mechanism and in the general construction, arrangement, and combination of parts of such apparatus.

In order that the invention may be clearly understood and readily carried into effect it is hereinafter described with reference to the accompanying drawings, in which:—

30 Figure 1 is a sectional front elevation of projector apparatus constructed in accordance with the present invention;

Figure 2 is a sectional side elevation of said apparatus;

35 Figure 3 is a plan view corresponding to Figure 1 but without the lamp-house, and showing the general arrangement of the gearing and the disc operating mechanism, and

40 Figure 4 is a detail view of a slightly modified form of gearing for use with apparatus for exhibiting posters and the like.

As shown the improved apparatus comprises a projector *a* and lamp-house *b* of any convenient construction, a rotatable picture-carrying disc *c*, a revolving shutter *d* and motor driven means for intermittently effecting the rotation of the disc and shutter at any desired speed after the manner of a kinematograph, or more slowly for the exhibition of posters or the like. According to the chief feature of this invention the operating means employed comprises a claw or arm *e* adapted to engage the perforations *c'* in the picture-carrying disc *c*, and slid-

ably mounted in a carrier *e'* in a suitable guide *f* and operated directly by means of a cam *g*. The cam *g* which may be of any suitable construction, may comprise a cylindrical disc *g* having a sinuous groove *g'* cut circumferentially in its peripheral edge, the said groove being also cut to varying depths so as not only to control the lateral movement of the claw or arm *e* but also to enable it to recede from the perforations *c'* in the disc *c* after each forward movement has been effected. The claw or arm may be controlled and pressed towards the cam by means of a suitable spring, or springs *h*. Thus, as the cam *g* rotates, the claw or arm *e* which is spring or gravity controlled, will be allowed to move back from the disc *c*, then out again to engage in the perforations *c'* in the disc, then forward to give the disc *c* its necessary intermittent movement, then back and out again, when the cycle of operations is repeated. By this means I am enabled to provide more silent operating mechanism than is possible where a Maltese cross or Geneva wheel is employed. The perforations *c'* may be provided in the periphery or other portion of the disc *c* itself, or in a metal disc *c* on to which the film may be clamped or secured by suitable means such as the rivets *c*. The film *c* itself may be of celluloid, or where a metal clamping disc *c* is employed a glass disc may be used. A suitable form of clamping device or hinged gate *i* is provided to keep the film *c* in its correct position in relation to the lens *j* of the apparatus. In some cases I may also provide a colour screen or a colour shutter in connection with the projector.

The apparatus is also provided with a motor driven fan or air blast producing apparatus *j* adapted to direct a stream of air through a nozzle *k* on to the gate of the projector and between the lens and the disc *c*, thus preventing overheating of the disc *c* and eliminating the risk of fire should the apparatus be kept in continuous operation for long periods of time. An automatic gravity actuated shutter *l* controlled by a centrifugal governor *m* or other means actuated by the driving gear, is also provided to close the gate *n* and shield the disc *c* from the heat of the projecting lamp *o* when the apparatus is at rest. In the construction shown the shutter *l* is secured by an arm *l'* to a flanged disc *l* rotatably mounted on the

shutter shaft w , and the governor m is secured to a disc l^2 revolving with the shutter shaft w . The governor m is pivotally mounted and when the shaft w is rotated 5 flies out under the influence of centrifugal force making contact with the flange of the disc l^2 and moving it to one side to open the gate of the projector.

Reducing gear may be provided if desired

- 10 so that the apparatus may be driven at any desired speed for different effects or classes of picture. For instance where it is desired to exhibit separate posters or the like, worm gearing of the kind shown in Figure 4 may
- 15 be substituted for the bevel and spur gearing shown in Figures 1 to 3 and interposed between the motor and the cam shaft p . In the case of the poster machine only one blade would be provided in the shutter
- 20 to mask the movement of the picture, or the light could be momentarily cut off.

In the particular construction illustrated with reference to Figures 1 to 3 the cam g is mounted on a shaft p which is driven 25 from the motor by means of a belt running on the wheel q . The shaft p , by means of bevel gear wheels r and s , also drives another shaft t , which by spur gearing u v , drives the shaft w on which the shutter d is mounted. The shaft p also carries another pulley wheel x which by another belt y and pulley z drives the fan j .

What I claim is:—

1. In exhibition apparatus, a rotatable 35 disc having thereon pictures to be displayed and provided with a plurality of perforations, a pin movable transversely to said disc and engageable in the perforations therein, a slide in which said pin is movable, a cam having a groove in which said pin is engaged and which controls the transverse movement of said pin relative to said disc, means yieldably maintaining said pin in engagement with said groove, and means 40 coacting with said pin and the sides of said groove for actuating said slide whereby said disc is progressively rotated.

2. In exhibition apparatus, a rotatable disc having thereon pictures to be displayed 50 and provided with a plurality of perforations, a pin movable transversely to said disc and engageable in the perforations therein, a slide in which said pin is movable, and a rotatable member having a cam groove therein and a second groove of varying depth in said cam groove, said slide engaging in said cam groove and operated thereby to progressively rotate said disc and said pin 55 engaging in said second groove and movable by such engagement, as said member is

rotated, into and out of the perforations in said disc.

3. In exhibition apparatus, a rotatable disc having thereon pictures to be displayed 65 and provided with a plurality of perforations, a pin movable transversely to said disc and engageable in the perforations therein, a slide in which said pin is movable, a rotatable member having a cam groove 70 therein and a second groove of varying depth in said cam groove, said slide engaging in said cam groove and operated thereby to progressively rotate said disc and said pin 75 engaging in said second groove and movable by such engagement, as said member is rotated, into and out of the perforations in said disc, and means carried by said slide and engageable with said pin to yieldably maintain the pin in engagement with said second groove.

4. In exhibition apparatus, the combination with a rotatable disc having marginally displayed pictures and a circular row of uniformly spaced perforations, of a pin 85 suited to engage in the mentioned perforations, a slide in which said pin is guided longitudinally, transversely of said disc, a cam having a groove controlling the rectilinear movement of said pin, springs in said slide forcing said pin against the cam 90 groove, and means coacting with said pin and the sides of the cam groove for actuating said slide whereby said disc is progressively rotated.

5. In exhibition apparatus, the combination 95 with a rotatable disc, an annular film secured concentrically thereon and including a plurality of radially disposed pictures, said disc having a circular row of like perforations evenly spaced and equi-distant 100 from the center, of a power driven shaft disposed in a plane at a right angle to the axis of said disc, a cylindrical cam on said shaft, said cam having a sinuous groove and a second groove of varying depth in the 105 bottom of the first groove, a slide interjacent said cam and disc, a pin operable in said slide, one end of said pin being engageable in the perforation of said disc and the other end in said second groove, springs urging said pin into the bottom of the second groove, and means carried by said pin engaging in the first groove whereby said pin and slide are moved laterally and in timed 110 relation to the raising and lowering of the 115 pin.

In testimony whereof I have hereunto signed my name.

JOHN EVANS.
